Inventor

Rufus M. Watkins.

UNITED STATES PATENT OFFICE.

RUFUS M. WATKINS, OF THAYER, MISSOURI.

DESIGN FOR A VEST OR SIMILAR ARTICLE.

SPECIFICATION forming part of Design No. 26,955, dated April 20, 1897.

Application filed February 12, 1897. Serial No. 623,192. Term of patent 14 years.

To all whom it may concern:

Be it known that I, RUFUS M. WATKINS, a citizen of the United States, residing at Thayer, in the county of Oregon and State of Missouri, have invented a new and original Design for a Vest, Jacket, or Similar Garment, of which the following is a specification.

This invention relates to a new and original design for a vest, jacket, or similar garment; and it has for its object to provide a design of this character that shall be both useful and ornamental.

The leading feature of the design resides in a vest, jacket, or similar man's or woman's garment having its front opening, above the line of buttons, formed with downwardly-curved edges and a narrow squared portion at its lower extremity, and a collar-piece edging the said front opening and having its inner edges coincident with the curved and straight portions of the edges of the front opening, said collar having its opposite lower extremities formed into V-points, projected below the plane of and divergently from the horizontal edge of the lower squared portion of the front opening in the garment.

In the drawing, the figure is a perspective

view of a man's vest embodying the herein-described design.

Referring to the drawing, the numeral 1 designates a man's vest having its front opening 2, above the line of buttons, formed with downwardly-curved edges and a narrow squared portion 3 at its lower extremity. A collar-piece 4, with duplicate side portions, 30 edges the opening 2 and has its inner edges coincident with the curved and straight portions of the edges of said front opening. The opposite lower extremities of the collar-piece 4 are formed into V-points 5, which project 35 below the plane of and divergently from the horizontal edge of the lower squared portion 3 of the front opening 2.

What I claim is—

The design for a vest, jacket or similar garment herein shown and described. 45

In testimony that I claim the foregoing as my own I have hereto affixed my signature in the presence of two witnesses.

RUFUS M. WATKINS.
